[57] CLAIM

The ornamental design for an insole, substantially as
shown and described.

DESCRIPTION

FIG. 1 is a bottom plan view of an insole showing my
new design;

FIG. 2 is a right side elevational view thereof;

FIG. 3 is a top plan view thereof;

FIG. 4 is a left side elevational view thereof;

FIG. 5 is a front elevational view thereof;

FIG. 6 is a rear elevational view thereof;
FIG. 7 is a cross-sectional view thereof as taken from
line 7—7 of FIG. 1.
